(57) **CLAIM**

The ornamental design for a fire pit as shown and described.

DESCRIPTION

FIG. 1 is a top, front, right perspective view of a fire pit of the present invention;

FIG. 2 is a front side elevation view thereof, the other three sides being identical; and,

FIG. 3 is a top plan view thereof.

The long-and-short broken lines form an unclaimed boundary. The even-length broken lines are for environmental purposes only and depict unclaimed subject matter which forms no part of the claimed design.

A bottom plan view has been omitted as it forms no part of the claimed design.
